(57) **CLAIM**

The ornamental design for a motor vehicle, toy and/or other replicas thereof, as shown and described.

DESCRIPTION

FIG. 1 is a front and right side perspective view of a motor vehicle, toy and/or other replicas thereof of the present invention with the convertible top open;

FIG. 2 is a rear and right side perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a front and right side perspective view thereof with the convertible top closed;

FIG. 9 is a rear and right side perspective view thereof;

FIG. 10 is a front view thereof;

FIG. 11 is a rear view thereof;

FIG. 12 is a left side view thereof;

FIG. 13 is a right side view thereof; and,

FIG. 14 is a top view thereof.

The wheels, headlights and taillights of the motor vehicle do not form part of the claimed design.
